AUTOMATIC VOLUME CONTROL CIRCUITS

Henricus Adrianus Broes, Eindhoven, Netherlands, assignor to N. V. Philips' Gloeilampenfabrieken, Eindhoven, Netherlands, a corporation of the Netherlands

Application June 25, 1937, Serial No. 150,277
In Germany July 28, 1936

5 Claims. (Cl. 250—20)

The invention relates to radio receiving systems with automatic and, in addition, with manual volume control.

In the usual systems with automatic volume control a negative control voltage which depends on the carrier wave amplitude of the received signal is supplied to one, or more, high, or intermediate frequency amplifying tubes. If this control voltage is taken so high that a substantially constant alternating voltage is supplied to the detector, there arises the drawback that for comparatively small carrier wave amplitudes the amplification is already considerably reduced with the result that noise due to Brownian movement, and the like, in the amplifying tubes is predominating. Besides, with weak signals a greater amplification is desired in order to supply to the detector a sufficiently high alternating voltage to obtain linear rectification. For these reasons it is desirable to choose the control voltage not too high, owing to which with an increasing carrier wave amplitude the alternating voltage supplied to the detector increases slightly. A proper adjustment of the manually operated volume control device permits, nevertheless, to obtain in this case always the desired output.

With the reception of weak signals the manually operated volume control device is adjusted, in general to a high output. When with the same adjustment a strong signal is received, considerable distortion is produced. This distortion is partly due to the fact that the low frequency amplifier is overloaded so that by adjusting the manually operated volume control device to a small output a reduction of the distortion may be obtained. As, however, the distortion also ensues from the fact that the diode detector is overloaded, it is not possible completely to remove the distortion in this way.

According to the invention, this drawback is obviated by providing a device for adjusting the control voltage for the automatic volume control which is supplied to one or more amplifying tubes, said device being mechanically coupled with the manually operated volume control device.

It is thus ensured that with any adjustment of the manually operated volume control device there is supplied to one or more amplifying tubes a control voltage such that the detector is prevented from being overloaded.

As the noise brought about due to Brownian movement, and the like, is substantially determined by the first amplifying tube of the system, it is particularly desirable to supply to the first amplifying tube of the system a control volt-

age which depends on the adjustment of the manually operated volume control device. To the amplifying tubes which follow said tube may be supplied, if desirable, a control voltage which does not depend on this adjustment.

In a superheterodyne receiving system there may be supplied, for example, to the radio frequency amplifying tube, or tubes, a control voltage which depends on the adjustment of the manual control device, and to the intermediate frequency amplifier a control voltage which does not depend on this adjustment.

In the drawing:

Fig. 1 shows a circuit employing the invention, and

Fig. 2 is a circuit embodying a modification.

Fig. 1 represents part of a superheterodyne receiving system. The oscillations amplified by an intermediate frequency amplifying tube 1 are supplied to a band pass filter which consists of 20 circuits 2 and 3 which are tuned to the intermediate frequency. The voltage across the circuit 2 is supplied through a coupling condenser 4 to a diode anode 5 which is arranged within a tube 6. This tube comprises, furthermore, a 25 second diode anode 7, a control grid 8, an anode 9 and a cathode 10. The oscillations supplied to the diode 5, 10 are rectified, and bring about across a resistance 11 a direct current voltage drop which depends on the carrier wave amplitude of the signal received. The voltage set up across the circuit 3 is supplied to the diode 7, 10 which serves for the demodulation of the oscillations received. Part of the audio frequency alternating voltage set up across the resistance 12 30 is supplied by a coupling condenser 13 to the control grid 8 which is connected through a leakage resistance 14 and a source of negative bias 27 to the cathode. A condenser 15 forms a by-pass for the intermediate frequency oscillations. The output of the audio frequency amplifier is adjusted 35 with the aid of a slide contact 16.

According to the invention, the direct current voltage drop across a variable part of the resistance 11 is supplied as a control voltage to the 45 high frequency amplifier. There is provided for this purpose a slide contact 17 which, as indicated by a dotted line 18, is mechanically coupled with the volume control slide contact 16. This mechanical coupling is such that a decrease of 50 that portion of the resistance 12 which is located between the slide contact 16 and the cathode 10 results in an increase of that portion of the resistance 11 which is located between the slide contact 17 and the cathode 10. The slide con- 55

tact 17 is connected through a filter, consisting of a resistance 19 and a condenser 20, to a conductor 21 which supplies the control voltage to the high frequency amplifier. When the manually operated volume control is adjusted to a smaller output a larger proportion of the variable direct current voltage set up across the resistance 11 is supplied to the high frequency amplifier. A control voltage which does not depend on the adjustment of the manually operated volume control is supplied to the intermediate frequency amplifier through a filter consisting of a resistance 22 and a condenser 23 and through a conductor 24.

15 Fig. 2 represents a system which differs from the system of Fig. 1 in that the control voltage which depends on the adjustment of the manually operated volume control is obtained by making the coupling condenser 4 variable, and, as is indicated by a dotted line 26, by mechanically coupling the condenser 4 with the manually operated volume control slide contact 16. In order to avoid that a variation of the capacity of the coupling condenser should influence the tuning, a 25 resistance 25 is connected in series with the coupling condenser. With a decrease of that portion of the resistance 12 which is located between the slide contact 16 and the cathode 10, the capacity of the coupling condenser 4 increases; 30 which results in that a higher alternating voltage is supplied to the diode 5, 10 and that, consequently, across the resistance 11 a higher direct current voltage is obtained. A control voltage for the intermediate frequency amplifier 35 which is independent of the adjustment of the manually operated volume control device is obtained in this case by supplying the direct current voltage drop across the resistance 12 to the intermediate frequency amplifier.

40 What is claimed is:

1. In a receiver of the type employing a plurality of cascaded signal amplifiers, a signal rectifier coupled to the last amplifier, means adjustably connected to the rectifier and functioning as a manual volume control device, a second rectifier arranged to have signals impressed thereon and adapted to derive a direct current voltage from rectified signals, means for controlling the magnitude of said voltage, additional means for 45 conjointly actuating said manual control device and said controlling means in such a manner that the said voltage magnitude is a function of the adjustment of the manual control device, means for applying said controlled voltage to the first 50 of said cascaded amplifiers, and a connection for applying the direct current voltage component of the rectified output of the first rectifier to an amplifier following said first of said cascaded amplifiers, said controlling means consisting of an adjustable condenser connected between the second rectifier and the said last amplifier.

55 2. In a receiver of the type employing a plurality of cascaded signal amplifiers, a signal rectifier coupled to the last amplifier, means adjustably connected to the rectifier and functioning as a manual volume control device, a second rectifier arranged to have signals impressed thereon and adapted to derive a direct current voltage from rectified signals, means for controlling the 60

magnitude of said voltage, additional means for conjointly actuating said manual control device and said controlling means in such a manner that the said voltage magnitude is a function of the adjustment of the manual control device, means for applying said controlled voltage to the first of said cascaded amplifiers, and a connection for applying the direct current voltage component of the rectified output of the first rectifier to an amplifier following said first of said cascaded amplifiers, said controlling means consisting of an adjustable condenser connected between the second rectifier and the said last amplifier.

3. In a receiver of the type employing a plurality of cascaded signal amplifiers, a signal rectifier coupled to the last amplifier, means adjustably connected to the rectifier and functioning as a manual volume control device, a second rectifier arranged to have signals impressed thereon and adapted to derive a direct current voltage from rectified signals, means for controlling the magnitude of said voltage, additional means for conjointly actuating said manual control device and said controlling means in such a manner that the said voltage magnitude is a function of the adjustment of the manual control device, means for applying said controlled voltage to the first of said cascaded amplifiers, a connection for applying the direct current voltage component of the rectified output of the first rectifier to an amplifier following said first of said cascaded amplifiers, an audio amplifier, said manual volume control device connecting the first rectifier to said audio amplifier, and a common tube envelope housing the electrodes of the two rectifiers and the audio amplifier.

4. In a superheterodyne receiver of the type including cascaded radio and intermediate amplifiers, a demodulator coupled to the intermediate amplifier and producing automatic volume control bias for the latter and audio voltage, an audio amplifier, means controlling the magnitude of audio voltage impressed on the audio amplifier; the improvement comprising a rectifier coupled to said intermediate amplifier and producing a second automatic volume control bias, means applying the second bias solely to the radio amplifier, and means, responsive to said controlling means, for adjusting the value of the second bias.

5. In a superheterodyne receiver of the type including cascaded radio and intermediate amplifiers, a demodulator coupled to the intermediate amplifier and producing automatic volume control bias for the latter and audio voltage, an audio amplifier, means controlling the magnitude of audio voltage impressed on the audio amplifier; the improvement comprising a rectifier coupled to said intermediate amplifier and producing a second automatic volume control bias, means applying the second bias solely to the radio amplifier, and means, responsive to said controlling means, for adjusting the value of the second bias, said last adjusting means consisting of a variable condenser coupling said rectifier and intermediate amplifier.
